UNITED STATES PATENT OFFICE.

HENRY MARCUS QUACKENBUSH, OF HERKIMER, NEW YORK.

DESIGN FOR A NUT-CRACKER.

SPECIFICATION forming part of **Design No. 18,888**, dated January 29, 1889.

Application filed November 19, 1888. Serial No. 291,287. Term of patent 14 years.

To all whom it may concern:

Be it known that I, HENRY MARCUS QUACKENBUSH, of Herkimer, in the county of Herkimer and State of New York, have invented a certain new and useful Design for a Nut-Cracker, of which the following is a specification.

My new design is clearly represented in the annexed drawing, which is a perspective view of a nut-cracker, in which are shown two levers, A A, of cylindrical form throughout their length, except near their connected ends, where a series of transverse grooves, a, is formed, which grooves cut away a small portion of the circumference, but leave the jaw portions substantially cylindrical. The handle portions of the levers are milled or knurled spirally, as shown at b, and terminate in tips

or ends c, of the form shown. Slight circumferential depressions d are formed between the grooved or toothed portions of the levers and the handle portions thereof.

The important and distinctive feature of the design is the cylindrical form of the levers, continuing from end to end, with only the slight break produced by the teeth.

What I claim is—

The design for a nut-cracker herein shown and described.

In witness whereof I hereunto set my hand in the presence of two witnesses.

HENRY MARCUS QUACKENBUSH.
